ATTACHMENT FOR A PAINT CONTAINER

Joseph R. MacDonald, 63 Franklin Road, Winchester, Mass. 18890, and Winfred A. MacDonald, 230 Essex St., Melrose, Mass. 02176

Filed Feb. 29, 1968, Ser. No. 10,788

Term of patent 14 years

Int. Cl. D9—99

U.S. Cl. D9—289

Fig. 1.

Fig. 2.

Fig. 3.

FIG. 1 is a top perspective view of an attachment for a paint container showing our new design;

FIG. 2 is a bottom perspective view; and

FIG. 3 is an enlarged, fragmentary sectional view taken on the line 3—3 of FIG. 1.

The broken line showing of a portion of a paint container and carrying handle in FIG. 3 is for illustrative purposes only.

We claim:

The ornamental design for an attachment for a paint container, as shown and described.
